UNITED STATES PATENT OFFICE.

LOUIS H. HOSBEIN, OF CHICAGO, ILLINOIS, ASSIGNOR TO M. H. DETRICK COMPANY, OF CHICAGO, ILLINOIS, A CORPORATION OF ILLINOIS.

FURNACE-ARCH CONSTRUCTION.

Application filed July 12, 1923. Serial No. 650,991.

To all whom it may concern:

Be it known that I, LOUIS H. HOSBEIN, a citizen of the United States, residing at Chicago, in the county of Cook and State of Illinois, have invented certain new and useful Improvements in Furnace-Arch Constructions, of which the following is a specification.

This invention relates to furnace construction, particularly to the portion forming the roof of a furnace, and commonly referred to as the furnace arch. The general purpose of the invention comprises the provision of a construction which will contribute to ignition and thorough combustion of fuel in the furnace; which is susceptible of installation and repair with facility; which will resist the destructive or disintegrating influences of temperature changes, intense heat, erosion, and the like to which furnace linings, particularly arch portions, are subjected; which is susceptible of wide modification and adaptation to a great variety of associated apparatus, such as steam boilers and the like; which presents minimum liability of metallic portions to injury from heat of the furnace and which contributes to economy in manufacture and maintenance.

A more specific object of the invention is the provision of a suspended arch construction designed particularly for use in connection with automatic stokers and having characteristics which induce the rapid coking and ignition of fuel upon its entering the furnace. In this connection it is a further object of the invention to eliminate the so-called ignition arch as a separate structural entity, and to incorporate it as a prolongation or continuation of the main or roof arch, thereby obviating the patch work heretofore resorted to to form the junction of the ignition and combustion arches and avoiding their separation, such as might occur in various previous constructions, due to differences in expansion, or shifting of supporting members due to difference in loading, and likely to result in leakage at points difficult of access and where important metallic structural members would ordinarily be exposed to the injurious influences of escaping heat and gases.

Another particular object of the invention is the provision of a construction for arches of the suspended type, including both an ignition arch and a combustion arch, and per-

mitting, to the maximum extent, the use of refractories of minimum cross-sectional size.

Another particular object is the provision of a construction for arches of the suspended type which will contribute in a desirable degree to the so-called "glazing" of the faces of the refractories exposed to the fire, attaining thereby augmented resistivity to erosive influences.

A further object of the invention is the provision of an improvement in suspended arch construction whereby the terminus of a suspended arch may be accommodated to boilers or other apparatus presenting a horizontally curved or otherwise irregular contour.

Other and further objects of the invention will be pointed out hereinafter, indicated in the appended claims, or ascertainable from the present disclosure by one skilled in the art. In the accompanying drawings, forming a part of the specification, I have illustrated a structure in which the invention is embodied, but it is to be understood that this particular disclosure is presented for illustrative purpose only, and while I regard it as a preferred embodiment of the invention, it is not to be accorded herein any effect serving to limit the invention which I purport to secure hereby, short of its true and most comprehensive scope in the art.

In said drawings,

Fig. 1 is a longitudinal sectional elevation of a furnace arch shown in association with steam boiler and chain-grate stoker elements, which are illustrated diagrammatically;

Fig. 2 is a transverse sectional elevation through the arch itself, such as might be taken on line 2-2 of Fig. 1;

Fig. 3 is a fragmentary top view of the rear portion of the arch, such as might be observed on line 3-3 of Fig. 1; and

Fig. 4 is a detail, showing in perspective one of the drop hangers.

Furnace arches of the type known generally as "suspended arches" possess certain distinctive advantages of substantial utility, and it is with this type of arch that the present invention is concerned. In the provision of the present improvements it has been my aim to preserve the characteristic advantages inhering in suspended arches as a class, to utilize these advantages to the fullest extent and to augment them with new

advantages. What these advantages are will be pointed out or indicated in the course of the description of the illustrative structure, from which the nature of the invention will be understood. On reference to the accompanying drawing, let it be understood that the reference numeral 10 designates side walls, of masonry construction, forming portions of the furnace chamber and boiler setting, and that the reference character 11 designates parts illustrative of the location of a steam boiler to which combustion products are to be conducted from the furnace chamber, said boiler being here illustrated as of the Wickes type. The reference numeral 12 designates an automatic stoker of the chain-grate type, here illustrated diagrammatically and including the hopper 12^a from which fuel is fed into the furnace through the fuel inlet 14 controlled by the adjustable gate 15. These are all conventional parts of apparatus well known in the art. The boiler and stoking mechanism are ancillary apparatus and do not in themselves form a part of my invention. Above the furnace chamber and across the same are supported the beams 16, here shown as carried on side walls 10. Shiftably engaged with the beams 16 are the bar hangers 17, certain of which support the top arch bars 18 having marginal flanges 18^a and others of which support the curved arch bars 18'. These arch bars extend longitudinally of the furnace and in aligned series. The top arch bars 18 are disposed at the upper and rearward portion of the arch structure, while the curved arch bars 18' are arranged in front of them toward the forward portion of the furnace and curve downwardly from substantially the plane of the top bars 18 toward the fuel inlet 14. The curved arch bars 18' thus present concave lower sides with upwardly curved marginal flanges 18^b. At the front of the furnace, adjacent the fuel hopper, a series of drop hangers 19 are suspended from one of the beams 16. These are suitable rigid frame members, one form being illustrated in Fig. 4, wherein will be seen it includes a vertical web bound at the top by a connecting flange 19^a pierced with apertures whereby the element may be attached to a hanger, the forward margin of the web being laterally flanged as at 19^b to afford laterally opening slots. A stop member 19^c depends below the web at its forward margin. At its upper and rearward portion the web is continued upwardly as a projection 19^d, bound on the forward margin by deflection of the flange 19^a. At its lower and rearward margins the web is provided with narrow lateral flanges 19^e of convex contour, and above them, after an interval 19^f, the rearward margin of the web is shaped with narrow lateral flanges 19^g which are longitudinally curved inward-

ly of the hanger, said flanges continuing to the end of the projection 19^d. These drop hangers are suspended in alignment with the bars 18' and with terminal projections 19^d preferably spaced away from the adjacent ends of said bars, the hangers being supported from one of the beams 16 by suitable attaching devices. The location of the flanges 19^g is such that they align with the flanges 18^b on the bars. Refractory tile 20 having parallel sides are suspended in courses on the bars 18 and 18', being retained by the flanges 18^a and 18^b which are received into undercut slots in the outer ends of the tile, the side faces of the tile being in contact so that a continuous fire resistant arch is provided as a top for the furnace chamber. In the intervals between the ends of adjacent bars similar tile are suspended, they being supported on bridge hangers 21 which have lower marginal flanges to engage in the slots of the tile and having projecting shoulders or ledges adapted to rest on the terminal tile which are supported on the bars, in such fashion that the tile carried on the bridge hangers will be retained in alignment and in contact with the tile to which they are juxtaposed. By withdrawal of the bridge hangers 21 and the tile carried by them, spaces will be afforded in the arch such as to permit the tile supported on the bars being slid off the latter and removed from the arch. The slots in the tile are of sufficient depth to permit the tile suspended on the curved bars 18' taking slightly angular relationship so that the courses of tile will conform generally to the curvature of those bars. For the purpose of taking up any excess divergence between the tile carried on the straight bars and those on the curved bars, wedge-shaped tile 22, which taper toward their lower ends, may be inserted as desired. Likewise, upon the flanges 19^g of the drop hangers, other parallel-sided tile 20 are suspended in courses aligning with those on the bars 18 and 18'. These courses of tile on the drop hangers conform to the contour of the curved flanges 19^g, so that their lower end faces form a continuation of the concave arch surface formed by the tile on the curved bars 18'. Space between the tile on the drop hangers and bars 18' may be filled by tile carried on bridge hangers 21 as described above. Upon the convex flanges 19^e of the drop hangers are suspended wedge-shaped tile 24. These tile have arcuate lower ends from which their front and rear faces converge toward the upper ends of the tile. I have illustrated these tile, and their suspension means, as of the sort described and claimed in my co-pending application Serial No. 489,411, although it may be observed that they may be of other sort, such as those illustrated in the co-pending application of

myself and Nathaniel D. Stevens, Serial No. 461,358. In the form illustrated herein the tile 24 are but one-half the width of the tile 20, so that two of them are required to complete the width of the course. They are maintained on the flanges 19^e by means of supplemental hangers 25, as described and claimed in my co-pending application above mentioned. The tile 24 of the outermost pair contact the stop 19^e at their forward sides, while those of the juxtaposed pair contact their rearward sides, filling the space between them and the other tile on the flanges 19^e. This construction gives the fire surface of the arch a contour curving reversely from the concave form produced by the tile on the curved bars 18' and on the flanges 19^e, and provides a convex depending ignition arch adjacent and sloping toward the fuel inlet. It will be observed that this convex portion adjacent the fuel inlet merges with an upbroken curve into the superjacent concave form of the arch, so that the entire under surface of the arch formed by the ends of the tile has a continuous, unbroken and regular contour.

In the construction of the rear end of the arch, in order to accommodate it to the horizontally curved form of the boiler, as illustrated in Fig. 3, I provide the transverse beam 26, which has a bracket 27 forming a support for the inner ends of diagonally arranged beams 28. These in turn support a short bridge beam 29 extending parallel to the beam 26. The rear end hangers for the arch bars are carried by these beams 28 and 29, said arch bars being of graduated lengths, as illustrated in Fig. 3. At their rearward extremities these arch bars carry nose brackets 30 secured thereto by wedges and forming upwardly extending elongations of the bars terminating in horizontally disposed shelves 30^a. These nose brackets, as described and claimed in my application above mentioned, have lateral arcuate flanges affording means of attachment for supplemental hangers 25 to support a convex fan end construction made up of tile 24 like those on the drop hangers. Cover tile 33 are laid upon the shelves 30^a to form a foundation course for the curtain wall. The latter, designated 31, is built up of ordinary fire brick resting on the tile 33. It may follow the marginal outline of the cover tile 33 or may be built to overhang them so as to give the rear end of the arch a more regular finish. By virtue of this construction the rear end of the arch may be brought into the desired proximity with the boiler tubes throughout the entire width of the arch, equalizing the distribution of gases to the boiler tubes.

The arch construction being assembled as above described with the addition of plates 23 which are inserted in the slots between the

flanges 19^e of the drop hangers, to prevent fuel from the hopper falling on top of the front end of the arch, the function of the arch in connection with the operation of the furnace will be described as follows: The stoking apparatus being operated in the customary fashion to feed fuel through the fuel inlet opening 14, it will be observed that this fuel enters the furnace chamber in close proximity to the depending arch surface formed by the tile 24. In this location the fuel is subjected to the intense heat radiated and reflected by the arch and walls to that point from the fuel and gases under combustion in the furnace chamber. The depending ignition arch concentrates this heat upon the fresh fuel with the result that its temperature is quickly raised to the point where its volatile constituents are driven off and the remaining solids soon ignited, meanwhile moving inwardly. As it progresses, the fuel is continued under the concentration of heat reflected by the concave portion of the arch, so that its maximum combustion is reached at an early stage in its course of movement. It will be observed that the contour of the arch recedes rapidly upwardly from the fuel bed at the rear of the narrow coking and ignition zone, so that the disposal of the refractories is out of the line of draft and at an elevation above the fuel bed such as to reduce their susceptibility to the destructive action of the heat. It is to be observed moreover that this rapid rise in the contour of the arch is accomplished without break in the regularity of the arch surface and without formation of a pocket such as is ordinarily formed by the angular junction of a depending ignition arch with a top arch. The present arrangement therefore contributes to the combustion efficiency of the furnace. One of the recognized advantages of the suspended arch resides in the freedom of the individual tile for relative movement so that they may adjust themselves incident to expansion and contraction of the structure, and thereby avoid extensive strains in it. The present invention makes further advantages use of this characteristic to preserve the integrity of the arch, by providing an arrangement wherein, throughout the entire extent of the arch wall, the refractories will adjust themselves to one another in such fashion as to preserve the continuity of the closure. Instead of having an ignition arch subject to contraction and expansion in one plane, and a roof arch subject to contraction and expansion in another and separate plane, whereby there is likelihood of opening up leaks between the two arches, the present invention provides a construction wherein the contraction and expansion of the roof arch and the depending arch are interdependent, so there is no line of cleavage along which the

structure might be inclined to open up. The construction therefore obviates the special arrangement and precautions heretofore requisite in the joining of the top arch and the ignition arch.

As is well known in practice, the resistance of many kinds of refractories to the influences which produce spalling is dependent to an extent on a glazing or apparent fluxing of the surfaces of the refractories exposed to the fire. It is important that such a glaze be produced on the refractories in a furnace arch immediately the arch is placed in operation, and that the glaze be preserved for the protection of the refractories. The provision of the present construction wherein the convex surface of the ignition arch merges gradually into the concave portion, and the latter, without interruption or break, into the flat top arch, affords an arrangement of the fire exposed surface which contributes to the formation of the protecting glaze uniformly over the entire surface, as the end surfaces of all the tile are similarly exposed to the fire bed. The construction contributes to uniformity in the heating of the arch by eliminating any corner or pocket at the junction of the ignition and roof arches, thus producing a uniform incandescence of the arch surface, which contributes to efficiency in combustion and uniformity in expansion of the refractory arch structure. The construction also facilitates repair or replacement of tile in the arch, as by withdrawal of the bridge hangers 21 injured or defective tile in any location in the arch may be removed and replaced without requiring extensive dismantling. All of the metallic elements in the structure are afforded protection from the heat by virtue of the fact that they are located where the air has full access to them, the webs of the drop hangers as well as those of the arch bars being effective to conduct heat away from the portions of those members seated within the slots of tile, and radiate it into the air. The construction is susceptible of incorporation in furnaces of any practical length and width simply by provision of supporting beams of proper length and use of the requisite number of arch bars 18 to afford the necessary length.

Features of construction herein shown but not claimed are claimed in co-pending application mentioned above and in my co-pending application Serial No. 527,248.

What I claim is:

1. In furnace arch construction, the combination of tile supporting members, tile suspended thereon to form a flat arch portion, hangers supported adjacent a wall of the furnace, wedge-shaped tile suspended thereon to form a depending convex arch portion adjacent the fuel inlet, curved sup-

porting members, and tile supported thereon in association to form a concave arch portion having its inner surface merging with and forming a continuation of the inner surfaces of the convex and flat arch 70 portions.

2. In furnace arch construction, in combination, refractories supported in position to form a flat arch portion, curved bars suspended adjacent the same and curving downwardly therefrom, hangers supported adjacent the lower extremities of the curved bars and tile supported on said hangers and bars to form an arch portion of merging concave-convex contour in continuation of 80 the flat arch portion.

3. In furnace arch construction, in combination, tile suspended over the furnace chamber to provide a flat arch portion, hangers disposed below the level of the flat arch portion and adjacent the fuel inlet, wedge-shaped tile supported on said hangers to form a convex ignition arch portion above the fuel inlet, tile supporting members disposed at different elevations between the convex arch portion and the flat arch portion, and tile suspended thereon to form a concave arch surface curving upwardly from the convex arch surface into alignment with the flat arch surface.

4. In furnace arch construction, in combination, tile suspended in association to form a flat arch portion above the furnace chamber, hangers supported adjacent the fuel inlet, tile supported on said hangers to form an ignition arch extending inwardly and upwardly from the fuel inlet, certain of said tile being of wedge shape with their broader ends disposed toward the furnace chamber, tile supporting members arranged between the ignition arch and the flat arch, and tile suspended thereon with their inner end faces forming a concave arch surface merging with the inner surface of the ignition arch and the inner surface of the flat arch.

5. In furnace construction, a depending arch portion comprising a plurality of laterally associated hangers, wedge-shaped tile suspended thereon with their broader end faces presented toward the furnace chamber, and parallel-faced tile suspended on said hangers above and contiguous to the wedge-shaped tile, said parallel faced tile being of substantially the same length as the wedge-shaped tile so that their lower end faces form an upward continuation of the arch surface formed by the inner ends of the wedge-shaped tile.

6. In furnace arch construction, the combination of a plurality of laterally associated hangers provided with flanges curved convexly toward the furnace chamber and superjacent flanges curved concavely toward the furnace chamber, wedge-shaped

- tile suspended on the convex flanges so that their inner ends form a salient arch portion, and parallel-faced tile suspended on the concave flanges so that their end faces 5 form a sloping reentrant arch portion merging with the salient arch portion.
7. In a furnace structure including the grate, the combination of tile supporting members arranged above the grate, tile suspended thereon to form a roof arch, and other tile suspended on the supporting members to form an ignition arch depending from the roof arch into proximity with the grate, the lower end surfaces of the tile in 10 the ignition arch merging with those of the tile in the roof arch.
8. In furnace arch construction, the combination of straight arch bars, tile suspended thereon in association to form a flat arch 15 portion, curved arch bars in alignment with the straight arch bars, tile suspended thereon with their lateral faces in contact to form a depending concave arch portion, tile supports arranged in alignment with said 20 curved arch bars, and tile suspended thereon with their lateral faces in contact to form an ignition arch portion, the tile on aligned tile supports and arch bars constituting continuous courses with the lower 25 end faces of contiguous tile flush.
9. In furnace arch construction, the combination with lateral supports, of beams supported thereon and extended diagonally 30 above the furnace chamber, arch bars suspended from said beams and terminating at graduated points longitudinally of the furnace at approximately uniform distance 35 from the beams, and refractories suspended on said arch bars in association to form the 40 furnace arch, the graduation in the length of the arch bars contributing variation in the rearward extent of the arch at different points transversely thereof.
10. Suspended arch construction comprising the combination with lateral supports, 45 of a beam carried thereon and spanning the furnace chamber, diagonal beams supported on said beam and extending diagonally above the furnace chamber, arch bars suspended from said diagonal beams and extending longitudinally of the furnace chamber to different extents rearwardly from the first mentioned beam but having substantially uniform overhang beyond the diagonal beams, and refractories suspended on said 50 arch bars so as to vary the extent of the arch in accordance with the length of the arch bars.
11. In furnace construction, the combination with lateral supports, 55 of beams supported thereon and extending diagonally above the furnace chamber, arch bars suspended from said beams and extending to different lengths longitudinally of the furnace but having substantially uniform overhang beyond the beams, refractories suspended on said arch bars to form a top arch, the refractories on different arch bars terminating at different points longitudinally of the furnace, and an apron wall built 60 upwardly from the rear ends of the arch bars.
12. In a boiler furnace installation including a boiler of irregular front contour, the combination of arch bars of different lengths 65 terminating in association with the boiler, refractories supported on the arch bars to form a furnace roof for conducting combustion products to the boiler, and a beam extending diagonally above the furnace 70 chamber and affording support for the arch bars at substantially uniform distance from their boiler ends.

In testimony whereof I have hereunto signed my name.

LOUIS H. HOSBEIN.
